TAPPING MACHINE

Melvin H. Emrick, Jamaica, N. Y.

Application June 5, 1948, Serial No. 31,253

4 Claims. (Cl. 10—129)

1

This invention relates to machines for operating tapping attachments to move the tap of the attachment toward and from the work. More particularly, the invention deals in a novel mounting of the tap supporting head in the machine so that the drive to said head is maintained stationary while the head moves axially with respect to the drive.

The novel features of the invention will be best understood from the following description when taken together with the accompanying drawing, in which certain embodiments of the invention are disclosed, and in which the separate parts are designated by suitable reference characters in each of the views; and in which:

Fig. 1 is a side view of a machine made according to my invention, with parts of the construction broken away.

Fig. 2 is an enlarged sectional view through the head end of the machine, and omitting the tap attachment.

Fig. 3 is a section on the line 3—3 of Fig. 2, showing parts of the construction in elevation and showing a slight modification; and

Fig. 4 is an enlarged broken sectional view similar to Fig. 2, but showing only parts of the construction.

This invention relates to machines of the general type and kind disclosed in Patent Number 2,079,371, dated May 4, 1937, and deals more particularly with the structure of the upper or head end of the machine, and still more particularly, with the mounting and operation of the tapping attachment supporting plate or adaptor. Further, with the provision of means for taking up the torque to which the attachment is subjected.

In the drawing, I have shown at 10, the base of the machine, in which is pivoted a foot pedal 11 for raising and lowering the tapping attachment or the tool supported therein with respect to the workpiece. Pivoted to the pedal is a rod 12 which extends to the operating mechanism, the arm of which is shown at 13, in other words, movement imparted to the rod 12 by pedal 11 is transmitted to arm 13. At 14 is shown a series of weights for counterbalancing the attachment to normally support the attachment in raised position. At 15 is shown an adjustable stop bolt limiting downward movement of the attachment. Extending upwardly from the base is a tubular column 16 through which the rod 12 passes, and supported at the upper end of the column is a head 17 supporting a suitable hood or housing 18, a drive motor 19 and a casing 20 in which the mechanism is arranged for support and guide of a tapping attachment 21.

On the motor shaft are a series of pulleys 22 over which is passed a belt, indicated at 23 in Fig. 2 of the drawing, which passes around another series of pulleys 24 secured to the upper end of a tube 25. The tube 25 is mounted for free rotation in upper and lower ball bearings 26 and 27

2

arranged in the casing 20. The tube 25 has two shoulders 28 and 29 on which are seated rings 30 and 31 to provide wide bearing supporting surfaces for the inner races of the bearings 26 and 27. A washer 32 is disposed upon the upper surface of the bearing 26 and a nut 33 is in threaded engagement with tube 25 to hold the bearing 26 in position. Another bearing retaining ring 34 is employed on the casing 20.

The lower end of the tube 25 fits flush with the lower bearing 27 and in said lower end is a bushing 35 for guiding the drive shaft 36 arranged within the tube 25. The shaft 36 has longitudinal key grooves 37 on opposed walls thereof, adapted to receive keys 38 for keying the shaft to the tube 25 while permitting axial movement of the shaft 36 with respect to said tube. The keys 38 are held in position by a tapered sleeve 39 slidably mounted on the tube 25, thus providing free coupling and uncoupling of the parts 25 and 36 whenever desired.

The lower end of the shaft 36 protrudes beyond the case 20 and has an enlarged socket portion 40, having a hexagon or other socket 41 for reception of the corresponding shank on the spindle of the attachment 21, as is generally known in this art. The enlargement 40 rotates freely within a bearing 42 in an adaptor head 43 to which the attachment 21 is secured in any desired manner. The arm 13 which is actuated by the rod 12 is coupled with the head 43, as clearly indicated in Fig. 2 of the drawing, so as to move said head with the attachment thereon downwardly and upwardly with respect to a workpiece supported on a table 44. The table 44 is adjustably clamped on the column 16 by a clamping lever 45 in order to position the workpiece at a predetermined distance with respect to the tap or other tool 21' of the attachment 21.

Also adjustable on the column 16 is a tool guide plate 46, adjustment being made through a clamping lever, as at 47. As far as relative positions of adjustment, the table 44 and plate 46 are only diagrammatically illustrated in the accompanying drawing. Suitable adjustment will be made to suit operating conditions. In said drawing, the head 43, as well as the attachment 21 is shown in an up position.

Secured to the head 43 is a stop feed screw 48 having adjustable screws 49 which operate in conjunction with a forked portion 50 of the case 20 in limiting downward feed movement of the tool 21' with respect to a predetermined workpiece. It will, of course, be apparent that the downward motion of the head 43, together with the attachment 21 and its tool 21' is controlled by the depression of the foot pedal 11. Upon release of the pedal, the weight 14 will automatically return the attachment and associated parts to the raised position.

With my improved machine, it will be apparent that the tube 25 with the pulleys 24 thereon maintain a fixed position with respect to the

pulleys 22, thus providing a constantly aligned drive between the pulleys through the belt 23. The shaft 36 is moved axially of the drive tube 25 in the operation of moving the tool toward and from the work. With this type of construction, the drive tube 25 can be firmly supported and yet mounted for free rotation in the supports therefor and in operating the tool to move the same toward and from the work, a comparatively light mechanism is employed, which will require a minimum amount of counterbalance.

In order to take up the torsional strains to which the head 43 may be subjected, particularly when the adaptor is utilized in conjunction with larger or multiple head tapping units, a head 43' is provided, to which is attached guide rods 51 which are slidably mounted in upper and lower bearings 52 and 53 of a case 20', substantially similar to the case 20. With this construction, an upper housing 18' is modified to a slight extent to accommodate the somewhat wider case construction, as clearly appearing in Fig. 3 of the drawing. As the other parts of the apparatus shown in Fig. 3 are the same as those shown in Figs. 1 and 2, like reference have been utilized to designate like parts.

It will, of course, be understood that the head 43' includes an adjustable stop screw, similar to the screw 48. The hood or housing 18, preferably includes a cover part 54 hinged, as seen at 55, to give access to the pulleys 24 in shifting the belt 23.

Having fully described my invention, what I claim as new and desire to secure by Letters Patent is:

1. In machines of the character described, a casing having vertically spaced walls defining upper and lower ends of the casing, bearings in said upper and lower walls, a tubular drive shaft rotatably mounted in said bearings, a driven shaft movable axially of the tubular shaft, a slide keying means between the driven shaft and said drive shaft, an adaptor plate carried by said driven shaft beyond said casing, the lower end portion of the driven shaft being freely rotatable in said plate, means coupled with said adaptor plate for moving the same and said driven shaft longitudinally of the drive shaft, an adjustable stop carried by and movable with said plate and engaging the casing in limiting movement of the adaptor plate and shaft in one direction, said keying means comprising a pair of keys in said drive shaft and operating in elongated slots at opposed sides of the driven shaft, and a single sleeve slidable on said drive shaft in retaining said keys in operative position.

2. In machines of the character described, a casing having vertically spaced walls defining upper and lower ends of the casing, bearings in said upper and lower walls, a tubular drive shaft rotatably mounted in said bearings, a driven shaft movable axially of the tubular shaft, a slide keying means between the driven shaft and said drive shaft, an adaptor plate carried by said driven shaft beyond said casing, the lower end portion of the driven shaft being freely rotatable in said plate, means coupled with said adaptor plate for moving the same and said driven shaft longitudinally of the drive shaft, an adjustable stop carried by and movable with said plate and engaging the casing in limiting movement of the adaptor plate and shaft in one direction, said keying means comprising a pair of keys in said drive shaft and operating in elongated slots at opposed sides of the driven shaft, a

single sleeve slidable on said drive shaft in retaining said keys in operative position, and a pair of rods coupled with said adaptor plate and extending above said upper wall and having sliding bearings in said casing for taking up torsional strains to which said plate is subjected.

3. In tapping machines of the character described employing an adaptor plate with which a tapping attachment is adapted to be coupled for movement toward and from a work-piece in the machine, a casing having spaced vertical walls defining upper and lower ends of the casing, bearings in said walls, a tubular drive shaft rotatable in said bearings, means fixing the position of said drive shaft in the casing, a driven shaft keyed to and movable axially of the drive shaft, said plate being mounted on the driven shaft beyond said casing, the lower portion of said driven shaft projecting below and being movable towards and from the lower wall of the casing and being freely rotatable in said plate, means for retaining the plate against axial movement on said driven shaft, the keying of the driven shaft to the drive shaft comprising a pair of keys in the drive shaft operating in elongated grooves in the driven shaft, a sleeve slidable on the drive shaft retaining the keys in operative position, and means coupled with said plate for moving said plate and driven shaft axially of the drive shaft in both directions.

4. In tapping machines of the character described employing an adapter plate with which a tapping attachment is adapted to be coupled for movement toward and from a workpiece in the machine, a casing having spaced vertical walls, defining upper and lower ends of the casing, bearings in said walls, a tubular drive shaft rotatable in said bearings, means fixing the position of said drive shaft in the casing, a driven shaft keyed to and movable axially of the drive shaft, said plate being mounted on the driven shaft beyond said casing, the lower portion of said driven shaft projecting below and being movable towards and from the lower wall of the casing and being freely rotatable in said plate, means for retaining the plate against axial movement on said driven shaft, the keying of the driven shaft to the drive shaft comprising a pair of keys in the drive shaft operating in elongated grooves in the driven shaft, a sleeve slidable on the drive shaft retaining the keys in operative position, means coupled with said plate for moving said plate and driven shaft axially of the drive shaft in both directions, and adjustable means carried by the plate and engaging the casing for limiting movement thereof and the driven shaft in one direction.
